Attorney

UNITED STATES PATENT OFFICE.

COLONEL J. CURTIS, OF OSAGE CITY, KANSAS.

PENCIL HOLDER.

Application filed February 8, 1924. Serial No. 691,436.

To all whom it may concern:

Be it known that I, COLONEL J. CURTIS, a citizen of the United States, residing at Osage City, in the county of Osage, State 5 of Kansas, have invented a new and useful Pencil Holder; and I do hereby declare the following to be a full, clear, and exact description of the invention, such as will enable others skilled in the art to which it 10 appertains to make and use the same.

The invention relates to pencil holders, and has for its object to provide a device of this character formed from a single piece of material, and constructed in a manner 15 whereby it may be easily and quickly attached to a conventional form of tablet at the glued end thereof, thereby allowing a pencil to be maintained with the tablet when not in use.

20 A further object is to provide a pencil holder adapted to be attached to a tablet and comprising a body portion adapted to be forced through the glued end of the tablet between the stiff back thereof and the 25 last page of the tablet and adhesively joined to the inner side of the back of the tablet. Also to provide the body portion with a bend disposed at a right angle to the body portion for engaging the glued end of the 30 tablet for holding the same in position during the gluing operation and relieving the strain on the glued connection of the body member.

35 A further object is to provide the right angularly disposed portion of the body portion with a semi-circular spring arm formed integral therewith, and adapted to receive and frictionally hold a pencil.

With the above and other objects in view 40 the invention resides in the combination and arrangement of parts as hereinafter set forth, shown in the drawing, described and claimed, it being understood that changes in the precise embodiment of the invention 45 may be made within the scope of what is claimed without departing from the spirit of the invention.

In the drawing:—

50 Figure 1 is a perspective view of a conventional form of tablet showing the device applied thereto and part of the tablet broken away to better show the structure.

55 Figure 2 is a side elevation of the tablet part being shown in section and showing the device in side elevation.

Figure 3 is a view of the glued end of the tablet.

Referring to the drawing, the numeral 1 designates a conventional form of tablet, 2 the front cover thereof, and 3 the relatively 60 stiff cardboard back. The sleeves 4 of the tablet, are secured together and to the front and back of the tablet by means of the gum strip 5 in the usual manner. It has been found that school children lose their pencils or misplace the same, and to obviate this difficulty and to maintain the pencil 6, when not in use, adjacent the pad 1, a pencil holder is provided, which holder comprises a rectangular shaped plate 7 adapted to be 65 inserted through the strip 5 into a position between the rear page of the tablet and the back 3 of the tablet, and adhesively joined to the inner side of the back 3 at 8, thereby rigidly securing the holder to the tablet. The outer end of the plate 7 is bent upon itself at 9 to form a right angularly disposed arm 10, which engages the strip 5, and not only limits the inward movement of the plate 7 to its proper position, but also forms 70 a bearing surface for one side of the pencil 6, and prevents side twisting of the plate 7 when the pencil is being inserted in the semi-circular roll 11 which frictionally holds the pencil.

75 It will be seen that the device is formed from a single piece of sheet metal, and the same may be easily and quickly applied to a tablet, and may be easily removed when the tablet has been used and the sheets of 80 paper removed therefrom, therefore the same holder may be used for many tablets. It will also be seen that the pencil 6 will be maintained attached to the tablet when not in use, in a manner where it cannot become 85 separated from the tablet and will always be in position where it can be easily removed and used. This pencil or pen holder can be fastened to the back of the tablet by gluing, stapling, clenching or various other 90 ways. This pencil or pen holder can be fastened to either end or either side of the back 100 of the tablet, book or the like.

95 The invention having been set forth what is claimed as new and useful is:—

105 The combination with a tablet having a cardboard back and a plurality of leaves, said back being secured to the leaves by an adhesive strip at one end thereof, of a pencil holder, said holder comprising a flat 110

metallic plate disposed between the cardboard back and the pieces of paper and adhesively joined to the inner side of the back, the outer end of said plate extending through an elongated slot in the adhesive strip, a right angularly disposed arm carried by the plate at its outer end and engaging the outer side of the adhesive strip and extending towards the front of the tablet and a pencil receiving roll carried by the

right angularly disposed arm and extending rearwardly, outwardly and forwardly. In testimony whereof I have signed my name to this specification in the presence of two subscribing witnesses.

COLONEL J. CURTIS.
